ELECTRIC FOOT MASSAGER

Clifford E. Grube, Niles, Ill., assignor to Associated Mills, Inc., Chicago, Ill.

Filed Oct. 20, 1965, Ser. No. 87,637

Term of patent 14 years

(Cl. D83—1)

FIG.1

FIG.2

FIG.3

FIG.4

FIG.5

FIGURE 1 is a top plan view of my electric foot massager;

FIGURE 2 is a side elevational view thereof, both sides being identical in design appearance;

FIGURE 3 is a bottom plan view thereof;

FIGURE 4 is an elevational view of one end thereof; and

FIGURE 5 is an elevational view of the other end thereof.

The dominant features of my design reside in the portions shown in full lines.

I claim:

The ornamental design for an electric foot massager, substantially as shown and described.
